SPRAYING APPARATUS FOR DENTAL, MEDICAL, AND LIKE PURPOSES

William Brewer, Upper Edmonton, England, assignor to Sparklets Limited, Westminster, England, a British company

Application September 22, 1937, Serial No. 165,215
In Great Britain December 9, 1936

1 Claim. (Cl. 299—95)

This invention relates to portable spraying apparatus of the kind such as is used in dentistry and medicine for the purpose of discharging in spray form under pressure a dentifrice, medicament or the like in the form of a liquid or solution. The invention particularly relates to apparatus of the type described in the British Patent No. 392,433, dated as of October 13, 1932, the said apparatus comprising a vessel for containing the solution to be sprayed and a head removably secured to the upper end of the vessel. A capsule (of the kind known under registered trade-mark as "Sparklet"), containing gas under pressure, such as carbon dioxide, is carried in a holder screwed onto the head and is adapted to be pierced by a hollow piercer in the head when the holder is screwed up, thereby to liberate the gas. The liberated gas passes through passages in the head and thence into the vessel where it acts to force the solution up a tube and through a valve-controlled passage in the head. The valve is controlled by a hand lever which operates against the action of a spring and which when actuated permits passage of the solution to an outlet pipe removably secured to the head and provided with a spraying nozzle.

In the said British Patent No. 392,433, the whole of the gas from the capsule is liberated at once into the vessel and in order to prevent liability of the vessel bursting under the pressure of gas, means are provided for creating an air-lock space which ensures that, when charging the vessel with solution, the latter cannot extend beyond a predetermined level and a sufficient space is left for the expansion of the liberated gas from the capsule.

Where, as in this arrangement, the whole of the gas is initially liberated into the vessel, the pressure of the ejected solution gradually decreases as it is used and, further, the air lock space required necessitates a larger vessel for a given quantity of solution than would otherwise be necessary.

The objects of the present invention are to provide means for obviating undue strain on the vessel by the liberated gas and for ensuring that the force of the stream of solution ejected is as uniform as possible throughout the period from the piercing of the capsule to its exhaustion.

The present invention consists in a spraying apparatus comprising a container for solution or the like, a head removably secured to the said container, a holder for a capsule containing a pressure medium and a nozzle both secured to the said head, and a manually operable valve be-

tween the container and the nozzle, wherein there is provided an auxiliary valve between the capsule and the container which is operable independently of the main valve by means of an actuating handle projecting through the head.

The apparatus is provided with a manually operable valve, arranged at a point between the gas container or capsule and the vessel, for controlling the passage of gas liberated from the capsule to the vessel containing the solution to be sprayed. A lever capable of manipulation by a finger of the operator is secured to the stem of the valve and a coil spring is arranged around the stem for maintaining the valve closed and for returning it to its closed position after actuation. By the provision of this valve, which is situated in the head of the apparatus, the gas from the pierced capsule can be admitted to the vessel in small quantities so as to ensure uniformity of pressure of the solution sprayed from the nozzle and to avoid undue strain on the vessel. The further advantages are attained that first the solution is not ejected too forcibly but the degree of pressure of the issuing spray can be regulated to suit individual requirements, secondly the vessel can be charged to its full capacity with the solution and need be of no greater dimensions than necessary for this purpose and thirdly gas from the same capsule (provided it is not exhausted) can be utilised for a fresh charge of solution or for different kinds of solution since the vessel may be replenished by unscrewing it from the head without liberating any gas other than that which has been admitted past the gas control valve.

The invention will now be more particularly described with reference to the accompanying drawings which show in Figure 1 an elevation partly in section of an apparatus of the type described in British Patent No. 392,433 and provided with a suitable construction of means in accordance with this invention.

Figure 2 is a side elevation of the head with the holder and nozzle removed;

Figure 3 is a view at right angles to Figure 2;

Figure 4 is a view corresponding to Figure 2 but showing the parts in section and

Figure 5 is a view at right angles to Figure 4 and corresponding to Figure 3 but shown partly in section.

Referring to the drawings, 1 is a vessel onto which is screwed a head 2 carrying two tubes 3 and 4 which project into the vessel to points adjacent its base. The solution in the vessel is expelled through the tube 3 and the gas from

the capsule is conveyed to the lower part of the vessel through the dip tube 4. A screw-threaded socket 5 is provided on one side of the head and its adapted to receive a holder 6 for a capsule 7 containing gas under pressure, for example carbon dioxide, the holder acting, when screwed up on the socket, to force the capsule onto a hollow piercer 8 whereby the gas is liberated into a passage 10 in the head. From this passage the gas 10 passes through branch passages 11 and 12 and thence into the dip tube 4.

The branch passage 11 is controlled by a screw-down valve 13, mounted in the head, the stem of which projects beyond the casing of the head 15 and has a lever 14 which can be manipulated by a finger of the operator for the purpose of operating the valve 13. To ensure against leakage of gas around the stem of the valve 13, a stuffing box nut 15 is provided which when screwed up 20 acts by its conical inner end to force a packing 16 tightly against the stem of the valve. A coil spring 17 is arranged around the stuffing box 18 of the valve, one end engaging the valve lever 14 and the other end entering into a slot 19 in the head 2. To open the valve the lever is moved 25 in a rotary direction and operates against the action of the spring, the strength of the latter being such as to permit only slight opening of the valve and to cause its return onto its seating after the release of the lever by the operator.

The valve assembly may readily be disassembled by removing the spring when the valve stem and the stuffing box nut are then free to be unscrewed from the head.

In order to operate the apparatus, the head is 35 unscrewed and the required liquid or solution poured into the then open neck of the vessel 1 and the latter then screwed onto the screwed boss 8 of the head. A capsule is placed in the holder and the latter screwed up to effect piercing 40 of the capsule by the piercer 8 whereupon the gas is liberated into the passages 10 and 11. Beyond this point no passage of gas is permitted until the valve 13 is operated and this is effected at the discretion of the operator who may 45 allow only small quantities at a time of the gas

to pass into the vessel 1 by a rapid actuation and release of the lever 14. The pressure of the expanded gas in the vessel 1 then forces the solution up the tube 3 and into a passage 20 in the head where it is prevented from passing 5 into a branch passage 21 communicating with the outlet tube 22 by the valve 23. This valve 23 is actuated in opposition to a spring 24, by a lever 25, the actuation of which raises the valve off its seating and allows the solution to pass into 10 the outlet pipe 22 from which it issues in spray form through a nozzle 26.

The outlet pipe is detachable and is made capable of rotation for the purpose of varying the direction of the spray.

It has already been proposed to provide a grooved screw-threaded member in the passage between the gas container and the solution container in atomisers for medicinal and dental purposes, means if desired being attached to the 20 said screw-threaded member and extending through the said solution container whereby the said member may be screwed inwardly to close the said groove.

What I claim is:

In spraying apparatus comprising a container for solution or the like, a head removably secured to the said container, a holder for a capsule containing a pressure medium and a nozzle both secured to said head, and a manually operable valve 30 between the container and the nozzle, the provision of an auxiliary manually operable valve allowing direct flow of pressure medium from the capsule to the container which is operable independently of the main valve by means of an 35 activating handle projecting through and carried by the head in such position that the said activating handle is capable of manipulation by a finger of the operator, a helical spring being arranged around the valve stem or the stuffing box therefor, one end engaging the activating handle and the other end engaging a stationary part, for example the head, of the apparatus for maintaining the valve closed and for returning it automatically to its closed position after operation. 40 45

WILLIAM BREWER.
